TIMING MECHANISM

William P. Gallagher, Carl Weber, and Paul E. Sutor, Chicago, Ill., assignors to International Register Company, Chicago, Ill., a corporation of Illinois

Application April 1, 1946, Serial No. 658,680

15 Claims. (Cl. 161—1)

1

This invention relates generally to timing mechanisms and it has particular relation to presettable timing mechanisms for effecting the operation of an alarm and a switch or either of them at a predetermined time.

It is usual to provide a clock in which the hour hand makes one revolution in twelve hours and to provide an alarm mechanism and a switch or both which can be set to operate at any time within the twelve hours. It is often desirable to have the alarm and/or switch to be operated at some time in the second twelve hours rather than in the first twelve hours. That is, it may be desirable to arrange for operation at, say, seven o'clock in the evening, the setting being made within twelve hours after this time in the preceding evening.

Such operation is desired where an electrical appliance, such as a coffee maker or a radio set, is to be turned on and an alarm given at a time more than twelve hours after the setting is made. Also, it might be desirable to turn on a light or lights at a predetermined time more than twelve hours after the setting is made. Such operation may be required for illuminating a sign, a store window or like application.

Accordingly the object of this invention generally stated is to provide a combination alarm and time switch which may be preset to operate at any time within a second twelve hour period after the expiration of a first twelve hour period which shall be simple, efficient and accurate in operation and which may be readily and economically manufactured and used.

Another object is to provide for operating mechanism such as an alarm and switch mechanism or either of them at a predetermined time more than twelve hours after a given time using timing mechanism which operates through one cycle in twelve hours.

A further object is to provide for manually selecting the operation and either the first or the second twelve hour interval.

A still further object is to shift an operating member from one position to another in the first twelve hour interval and to shift it to a third position in the next twelve hour interval to effect the desired operation at that time.

Another object is to provide for shutting off the alarm mechanism without changing the position of the switch.

Other objects of this invention will in part be obvious and in part appear hereinafter.

This invention is disclosed in the embodiment thereof shown in the accompanying drawings and

5 5

2

it comprises the features of construction, combination of elements and arrangement of parts which will be exemplified in the construction hereinafter set forth and the scope of the application of which will be indicated in the appended claims.

In general the invention comprises a timing motor, such as a synchronous motor, which is arranged to drive a time wheel through one revolution in twelve hours. Conventional hour and minute hands are provided for cooperation with the time wheel and to indicate with respect to a dial in a conventional manner the time. A manually presettable, adjustable dial is arranged to carry a trip pin the position of which controls the functioning of the tripping mechanism.

A spring biased multiple stop plate is arranged to be locked manually in an inoperative position and to be moved manually to various operative 20 positions as well as to be moved automatically to these operative positions after it has been unlocked from its inoperative position. Assuming that the mechanism is to operate at a time in the second twelve hour period, the adjustable dial is set to the desired time and the trip pin carried thereby cooperates with the trip mechanism on the time wheel during its next revolution for releasing the multiple stop lever to move from one position to another. However, at that time no 25 further operation takes place in so far as the alarm and switch mechanism is concerned.

When the time wheel completes a second revolution and the tripping mechanism carried thereby engages the trip pin, the multiple stop plate is released to move to a position where the alarm is released and the switch is operated.

The multiple stop plate then can be moved manually so as to shut off the alarm while maintaining the switch in the operated position.

40 Additional manually operable means is provided for cutting out or shutting off the alarm mechanism. Such operation may be desirable where only the switch operation is required.

It will be understood that, while the present invention is described in connection with a switch mechanism that is arranged to be operated from the open to the closed position at the presettable time, the arrangement may be such that the switch is operated from a closed to an open position. Moreover, while a synchronous electric motor is disclosed as providing the driving means for the timing mechanism, it will be understood that other types of motor including a spring motor can be used.

For a more complete understanding of the na-

ture and scope of this invention reference may be had to the following detailed description taken in connection with the accompanying drawings in which:

Figure 1 is a view, in front elevation, of a clock in which the present invention is incorporated;

Figure 2 is a view, in rear elevation, of the clock shown in Figure 1;

Figure 3 is a view, in side elevation, of the clock shown in Figure 1;

Figures 3a-3e show different positions of the control lever;

Figure 4 is a view, in rear elevation, of the clock mechanism with the back plate removed;

Figure 5 is a detail sectional view taken along the line 5—5 of Figure 4;

Figure 6 is a view, in front elevation, of the mechanism mounted on the back plate, the case having been removed;

Figure 7 is a view, in front elevation, of the mechanism shown in Figure 6 with the adjustable dial removed and showing the trip mechanism mounted on the time wheel;

Figure 8 is a detail sectional view taken along the line 3—3 of Figure 7 and illustrating the mechanism in the case;

Figure 9 is a detail sectional view taken along the line 9—9 of Figure 4;

Figure 10 is a detail sectional view of one of the adjusting knobs;

Figure 11 is a view, in end elevation, at an enlarged scale of the adjusting knob;

Figure 12 is a view, in front elevation, of the switch mechanism, terminals and insulating mounting block;

Figure 13 is a detail sectional view taken along the line 13—13 of Figure 12;

Figure 14 is a view, in front elevation, of the base plate and certain of the mechanism mounted thereon with the control lever in the position shown in Figure 3d;

Figures 15 and 16 are detail sectional views taken along the line 15—15 of Figure 14 showing how the control lever is released to permit movement from one position to another;

Figure 17 is a view, in front elevation, of the base plate and certain of the mechanism mounted thereon with the control lever in the position shown in Figure 3c;

Figure 18 is a view similar to that shown in Figure 14 but with the control lever in the position shown in Figure 3a;

Figure 19 is a view similar to that shown in Figure 17 but with the control lever in the position shown in Figure 3b; and

Figure 20 is a view similar to that shown in Figure 14 but with the control lever in the position shown in Figure 3e.

Referring now particularly to Figures 1 through 4 of the drawings, it will be noted that the reference character 21 designates a clock case which may be of metal or plastic. The case 21 carries a numbered face plate or dial 22 with which a minute hand 23, mounted on a shaft 24, and an hour hand 25 cooperate to indicate the time in a twelve hour period. Attention is called to the graduations indicated at 26 along the inner rim of the dial 22 which are divided into quarter hour intervals.

An adjustable dial 27 is arranged to be rotated manually, as will be set forth hereinafter, for presetting the mechanism to operate at the desired time. The dial 27 carries an index 28 which can be set to the desired time with respect to the scale 26 and the dial 22.

The face of the clock is provided with a cover glass 29 which may be held in place by a retaining ring 30. As shown more clearly in Figure 9 the retaining ring 30 may be provided with integrally formed tabs 31 which project into apertures 32 in the case 21 and are bent over inside thereof for holding the ring 30 and therewith the cover glass 29 in place.

At one side of the clock case 21 a control lever 33 projects. The control lever 33 has various positions as indicated in Figures 3a-3e to which detailed reference will be made hereinafter. Suitable conductors 34 extend from the clock case 21 for energizing the synchronous electric motor incorporated therein. It will be understood that the conductors 34 may be connected to a suitable source of alternating current such as a 60 cycle-110 volt source.

In Figure 2 it will be noted that the clock is provided with a back plate 38, which may be formed of metal and that it has an inwardly and upwardly extending flange 39 that projects into a slot 40, Figure 9, for holding the upper side in place. The major portions of the sides and top of the back plate 39 are turned inwardly as indicated at 41 to stiffen it and to provide a closer fit with the inner wall of the case 21. Screws 42, Figure 2, serve to hold the bottom of the back plate 38 in the case 21 and permit ready removal thereof.

The back plate 38 has an inwardly deformed section 43 which is apertured at 43' for receiving a socket portion 44 of an insulating housing which carries the switch that will be described hereinafter. Slots 45 are provided in the portion 44 of the housing that are spaced apart so as to receive a conventional plug attached to conductors that are connected to the electrical device which is to be controlled. For example, the conductors connected to the plug may be connected to a radio set, electrical appliance, lamp or the like which is to be energized or de-energized at the time the switch operates. It will be understood that the energy for operating the device may be obtained through the conductors 34.

The inwardly deformed section 43 of the back plate 38 may be provided with a generally semi-circular opening 46 through which a raised section 47 of the insulating housing may project. The section 47 has an aperture 48 therein through which the conductors 34 extend into the switch housing for connection to terminals therein, as will be described hereinafter.

An adjusting knob 51 is mounted on the rear end of the shaft 24 and serves to permit manual setting of the minute hand 23 and hour hand 25 in conventional manner. As shown in Figures 10 and 11 the knob 51 has a barrel 52 integrally formed therewith for slipping over the rear end of the shaft 24 with a relatively close fit. The shaft 24 is longitudinally slotted as indicated at 53 to facilitate application of the barrel 52 and to provide a certain degree of resiliency for holding the knob 51 thereon. One side of the slotted shaft 24, as indicated at 54, is longer than the other side for projecting through a semi-circular aperture 55. This construction permits the knob 51 to rotate the shaft 24 on the application of torque thereto. At the same time it permits ready assembly of the knob 51 on the shaft 24. If desired, after assembly the semi-circular end 54 of the shaft 24 may be peened over to prevent ready removal of the knob 51.

A control set knob 55', similar to the nob 51, is mounted in a like manner on the rear end of a shaft 56 which, as will hereinafter appear, carries a dial gear for adjusting the position of the dial 27.

The back plate 38 is apertured as indicated at 57 for receiving an alarm cut-out slide 58. The slide 58 is shown more clearly in Figure 5 where it is illustrated in the alarm release position.

A mounting screw 59 extends through the back plate 38 and is secured in place by a nut 59'. As shown in Figure 5 the mounting screw 59 serves to hold a bell 60 in place on the inner side of the back plate 38. As is shown more clearly in Figure 8 the central rear part of the bell 60 is deformed outwardly as indicated at 61 for receiving the mounting screw 59 and providing a limited area of engagement with the back plate 38. The engagement of the section 61 with the back plate 38 is the sole support contact with the bell 60 thereby improving its tone.

As indicated in Figure 3 one side of the case 21 is provided with a generally rectangularly shaped opening 62 through which the control lever 33 projects. An indicator plate 63 is carried by and is movable with the control lever 33. As shown, the indicator plate 63 carries numbers such as 12 and 24 which register with a side aperture 64 to indicate the position occupied by the control lever 33. When the figures 12 are visible, the clock is set to operate the alarm and/or switch at the preset time within the next 12 hours. When the figures 24 appear in the opening 64, the alarm and/or switch will be operated at a preset time in the second 12 hour period.

As shown in Figure 4, when the back plate 38 is removed, a base plate 68, preferably formed of metal, is visible. The base plate 68 is provided with a nose 69 which, as illustrated in Figure 9, is arranged to fit in a slot 70 in the under side of the top of the case 21. Screws 71 serve to hold the base plate 68 in position in the case 21 and on removal thereof permit withdrawal of the base plate 68 and the mechanism mounted thereon.

It will be observed that the base plate 68 is slotted as indicated at 72 with the edges of the intermediate section 73 turned upwardly for receiving conductors 74. This construction is provided to insure that the conductors 74 do not touch the bell 60, the rim of which extends over the section 73, thereby impairing its tone.

The conductors 74 serve to energize a synchronous electric motor 75 which may be of conventional construction in so far as the present invention is concerned. The motor 75 is held in position on the base plate 68 by screws 76.

The motor 75 is arranged to drive a gear wheel 77 through a suitable reduction gear train (not shown) at a speed of one revolution per hour. The gear wheel 77 is carried by a shaft 78 which projects through the base plate 68 and carries at its forward end a pinion which will be referred to hereinafter. The gear wheel 77 drives a gear wheel 79 that is fast on the shaft 24 which, it will be recalled, carries the minute hand 23.

On the lower left hand corner of the base plate 68 is mounted an insulating switch mounting block or housing 80 from which the projections 44 and 47, previously referred to, extend and with which they are integrally formed. The housing 80 is formed of suitable insulating material such as "Bakelite." It is held in place on the back plate 68 by a screw 81.

Integrally formed with the housing 80 is an

arm 82 which extends upwardly and to the left to form a bearing for one end of a shaft 84. The control lever 33 is rockably mounted on the shaft 84, as will hereinafter appear.

Referring now to the Figures 12 and 13, the construction of the insulating switch mounting block or housing 80 is shown in more detail. It will be noted that the housing 80 has a cavity 85 on the bottom of which a switch blade bracket 86 is secured. A terminal 87 is likewise secured to the bottom of the cavity 85. Terminal screws 88 and 89 serve to hold the bared ends of the conductors 34 in connection with the bracket 86 and terminal 87 respectively. A switch blade 90 of suitable resilient conducting material extends from the bracket 86 through a slot 91 in the rim of the housing 80. The switch blade 90 carries a contact button 92 which engages a contact button 93 that is carried by a contact bracket 94. The contact bracket 94 extends through the slot 91 in the housing 80 and is attached to a terminal 95. Contact spring fingers 96 and 97, as shown in Figure 13, are connected to the terminals 95 and 87 respectively and are held thereto and in the housing 80 by screws 98 and 99. It will be noted that the inturned ends of the contact spring fingers 96 and 97 register with the slots 45 and are arranged to be engaged by the prongs of the plug that is attached to the conductors connected to the mechanism thereby energized as previously described. It will now be apparent that the contact spring fingers 96 and 97 are energized from the current source through the conductors 34 when the switch blade 90 is in the position shown in Figure 12 with the contact buttons 92 and 93 in engagement.

It will also be observed that the conductors 74 which serve to energize the motor 75 are connected for energization to the conductors 34 by the terminal screws 88 and 89.

In order to interrupt the circuit to the contact spring fingers 96 and 97, provision is made for separating the contact button 92 from the contact button 93 by moving the switch blade 90 in a counterclockwise direction, as viewed in Figure 12. For this purpose the outer end of the switch blade 90 is apertured as indicated at 100 for receiving therethrough a nose portion 101, Figure 4, of a switch operating arm 102 that is rockably mounted on the shaft 84. The arm 102 is formed preferably of suitable insulating material such as "Bakelite." The manner in which the arm 102 is operated to control the position of the switch blade 90 will be set forth in detail hereinafter.

As shown in Figure 13 an insulating cover 103 closes the cavity 85 in the housing 80. It is formed of suitable insulating material such as fish paper.

As shown in Figure 6, the adjustable dial 27 comprises two plates 107 and 108 which may be fastened together by rivets 109. The plate 107 is of smaller diameter than the plate 108, is provided with a suitable attractive finish and carries the index 28. The outer edge of the plate 108 is toothed as indicated for cooperation with the teeth of a shrouded dial gear 110 that is mounted for rotation with the shaft 56. It will now be apparent from a consideration of Figure 5 that rotation of the nob 55' on the shaft 56 causes rotation of the shrouded dial gear 110 which in turn effects rotation of the dial 27. It is desirable that there be a certain amount of friction in the rotation of the shrouded dial gear 110 so that it will remain in any position to which it may be rotated. For this purpose the

forward end of the shaft 56 projects through a hub 111 that is fastened to the base plate 68 and which is surrounded by a coil compression spring 112 that reacts between the base plate 68 and a cone-shaped washer 113 that bears against the backside of the shrouded dial gear 110. It will be understood that the spring 112 acting through the washer 113 provides sufficient frictional drag on the dial gear 110 as to hold it in any position at which it may be operated and that it likewise holds the dial 27 in corresponding position.

The adjustable dial 27 carries a triangularly shaped trip pin 114, Figure 6, which extends rearwardly from the toothed disc 108. The trip pin 114 is, of course, movable with the adjustable dial 27 and serves, as will hereinafter appear, to release the trip mechanism for causing the desired operation of the alarm and switch mechanisms.

The adjustable dial 27 is relatively flexible. It is desirable that it be held substantially in the plane shown in the drawings for proper operation. The forward face of the disc 108 rotates immediately back of the inner edge of the dial 22, Figure 1, and thus is held from moving forwardly thereby. Tabs 115 and 116, Figure 7, are cut out of the base plate 68 and are bent forwardly thereto in such position as to provide a slight clearance space between the ends and the rear surface of the disc 108. In addition a nose 117 is integrally formed with and projects from a control lever bracket 118 which forms a support for the other end of the shaft 84 and which may be secured to the base plate 68 by screws 119. Thus a three-point support is provided by the tabs 115 and 116 and the nose 117 for limiting the rearward movement of the dial 27.

As shown more clearly in Figure 14 the shaft 78 which, it will be recalled, is driven at a speed of one revolution per hour, carries at its forward end a pinion 123 which meshes with an idler gear wheel 124 that in turn drives a pinion 125. The pinion 125, Figure 7, meshes with and drives a time wheel 126 in a clockwise direction as indicated by the arrow 127. The gear reduction is such that the time wheel 126 makes one revolution in twelve hours.

As shown in Figure 8 the time wheel 126 is mounted for rotation with a hub 128 that is rotatably mounted on a tubular bearing sleeve 129 from which a circular flange 130 projects. The flange 130 is secured as by rivets 131 to the back plate 68.

Rotatably mounted on another step on the hub 128 is a ratchet wheel 134, Figures 7-8, which carries an arm 136, Figure 5, from which a trip pin 137 extends through an aperture 138, Figure 14, in the base plate 68. The trip pin 137, as shown, has a square cross section and its outer end is reduced for receiving one end of a coil tension spring 140, Figure 5, the other end of which is anchored to a tab 141 struck rearwardly from the base plate 68, Figure 4. The spring 140 serves to bias the stop pin 137 against a stop 142, Figure 14, that is formed with base plate 68 and projects into the aperture 138.

Mounted on the rear side of the time wheel 126, Figure 8, is a pawl 143 which is arranged to cooperate with the teeth of the ratchet wheel 134. The pawl 143 is carried by a pin 144 which projects through the time wheel 126 and carries at its other end a pawl actuating arm 145. It will be understood that the pawl 143 is movable with the arm 145 through the pin 144 which is

rockably mounted on the time wheel 126. The arm 145 is biased in a clockwise direction by a coil tension spring 146 which extends between a hook portion 147 of the arm 145 and a tab 148 that is struck out of the time wheel 126. The spring 146 serves to rock the pawl 143 into engagement with the teeth of the ratchet wheel 134. This engagement takes place once during each revolution of the time wheel 126, as will hereinafter appear. Otherwise the pawl 143 is held out of engagement with the teeth of the ratchet wheel 134 by an actuating member 149 one end 150 of which engages a nose portion 151 of the arm 145. The actuating member 149 is rockably mounted on a pin 152 which extends from the time wheel 126. The actuating member 149 is biased in a clockwise direction about the pin 152 by a coil tension spring 153 which is connected between a hook portion 154 of the member 149 and a tab 155 which is struck up from the time wheel 126. It will be understood that the spring 153 holds the actuating member 149 in the position shown in Figure 7 with the end portion 150 in engagement with the nose 151 of the arm 145, thereby holding the pawl 143 out of engagement with the ratchet wheel 134 against the biasing force of the spring 146.

In order to move the actuating member 149 a dog 156 is pivoted thereon by a pin 157. The dog 156 has a nose portion 158 which is arranged to be engaged by the trip pin 114 either when the time wheel moves the dog 156 to the proper position or the dial 27 is manually rotated to preset the same.

It is desirable that no movement of the actuating member 149 take place when the trip pin 114 is moved past the dog 156 in a clockwise direction. For this purpose the dog 156 is provided with inclined edge 159 leading to the nose 158 and the dog 156 is slotted as indicated at 160 to permit a slight movement relative to the pin 152. It will be understood that when the trip pin 114 is moved in a clockwise direction relative to the dog 156, it will merely slide along the inclined edge 159 and the dog 156 rocks in a clockwise direction as permitted by the slot 160 until it passes the tip of the nose 158.

As shown in Figure 7 the dog 156 may be biased by a coil compression spring 162 which reacts between the dog 156 and a tab 163 struck up from the actuating member 149.

When the nose 158 is moved into engagement with the trip pin 114, either as by rotation of the time wheel 126 in the clockwise direction or a movement of the trip pin 114 in a counterclockwise direction, the trip pin 114 engages a radial face 161 of the dog 156. Continued relative movement of the trip pin 114 and the dog 156 causes the actuating member 149 to be rocked in a counterclockwise direction thereby withdrawing the end 150 of the member 149 from engagement with the nose 151 of the arm 145 and permitting the spring 146 to move the pawl 143 into engagement with the teeth of the ratchet wheel 134.

As the relative movement of the trip pin 114 and the dog 156 continues the actuating member 149 rocks and spring 153 is tensioned. The actuating member 149 is thus moved about the pin 152 until the nose 158 is moved past the trip pin 114. The actuating member 149 is then released for movement with a snap action under the force of spring 153 so that the end 150 of the actuating member 149 strikes the nose 151 of the arm 145 a blow or impacts the same. A corresponding

movement is imparted through the pawl 143 to the ratchet wheel 134 and the stop pin 137, Figure 14, carried thereby is moved away from the stop 142. This movement of the stop pin 137, as will hereinafter appear, serves to release control mechanism which in turn effects operation of the alarm and switch mechanism.

Referring now to Figure 14 it will be observed that a multiple stop plate 167 is there shown. The stop plate 167 is fast on shaft 84 and is arranged to be biased in a clockwise direction by a coil spring 168 one end 169 of which bears against the lower portion of the control lever bracket 118 while the other end 170 bears against a tab 171 that is struck up from the plate 167. The plate 167 has an arcuate opening 172 along the inner edge of which flattened stop portions 173 and 174 are located for successively engaging the stop pin 137. The outer surface of the arcuate slot 172 has a flat surface 175 intermediate the stops 173 and 174. The purpose of the flat surface 175 is to limit the outward movement of the stop pin 137 when it leaves the stop 173 and to direct it into engagement with the stop 174 when the stop plate 167 is moved in a clockwise direction by the spring 168. The lower end of the arcuate slot 172 is closed by a tail portion 176 which serves to strengthen the plate 167 and hold the portions thereof forming the slot 172 in alignment. A stop, in the form of a tab 177 struck up from the base plate 68, serves to limit the movement of the stop plate 167 in a clockwise direction.

With a view to moving the stop pin 137 out of engagement with either of the stops 173 or 174 with which it may be engaged for the purpose of manually adjusting the position of the stop plate 167 a flat edge 178 of a pin release arm 179 is arranged to engage the stop pin 137 in either of these two positions. The pin release arm 179 is rockably mounted on the stop plate 167 by a pin 180. A spring 181 serves to hold the pin release arm 179 in the retracted position. It will be observed that the spring 181 is fastened between a tab 182 struck up from an inner extension of the control lever 33 and a hook 183 extending from a shoulder portion 184 integrally formed with the pin release arm 179.

The pin release arm 179 is moved by the control lever 33 through the agency of a nose 185 integrally formed with the latter and bearing against the shoulder 184. The control lever 33 has limited movement relative to the stop plate 167 as permitted by a notch 186 at the inner end in which the tab 171 extending from the stop plate 167 projects. Thus when the control lever 33 occupies the position shown in either Figure 17 or Figure 19, movement of the control lever 33 in a clockwise direction causes the pin release arm 179 to be moved so as to lift the stop pin 137 out of engagement with the stops 174 and 173 respectively thereby permitting the spring 168 to move the stop plate 167 to the next position.

As shown in Figures 14, 15 and 16 the control lever 33 has a rearwardly turned shoulder 190 which, in the position shown in Figure 14, is arranged to abut an extension 191 of the base plate 68 thereby holding the control lever in the position shown in Figure 3d. When it is desired to move the control lever to the position shown in Figure 3e, the control lever 33 is shifted toward the front, as shown in Figure 16, against the spring 168 until the shoulder 190 clears the extension 191. The spring 168 then moves the

stop plate 167 until it rests against the stop 177, Figure 14.

Mounted for rotation with the shaft 84 and the stop plate 167 is a cam 192, Figures 5-17, having a nose 193 that is arranged to engage a pin 194 which extends through the switch operating arm 102, Figure 4, for moving the same so as to separate the contact buttons 92 and 93, thereby opening the switch. The switch operating arm 102 is slotted as indicated at 195, Figure 17, so as to permit relative movement with respect to the shaft 84.

As shown more clearly in Figure 4, a stop 196 is integrally formed with the base plate 68 for cooperating with the shoulder 190 of the control lever 33 for holding the same in the position shown in Figures 3b and 19. When it is desired to move the control lever 33 to the position shown in Figures 3a and 18, the control lever 33 is moved, as indicated in Figure 16, to such position that the shoulder 190 clears the stop 196 whereupon the control lever 33 is moved against the biasing force of the spring 168 until the shoulder 190 engages the stop 196, as shown in Figure 18. In this position neither the alarm nor the switch mechanism is operable.

The mechanism for ringing the bell 60 will now be described. As shown in Figure 14 a bell hammer 199 is arranged to strike the inside of the bell 60, Figure 5. The hammer 199 is located on the rear side of the base plate 68 and is carried by an arm 200 which projects from the front side of the base plate 68 through an aperture 201 therein. The aperture 201 is generally rectangular to permit the hammer 199 and arm 200 to rock for striking the bell 60. At its upper end the arm 200 is rockably mounted by a screw 202 on a tab 203 which is struck up from the base plate 68. For reciprocating the arm 200 shoulders 204 and 205 are provided on a connecting rod 206 which is arranged to be oscillated with the arm 200 between the shoulders 204 and 205. The connecting rod 206 has an inverted V-shaped notch 207 which interfits with an off-center pin 208 carried by a pinion 209 which forms a part of the gear train that is driven by the motor 75. It will be understood that the rotary movement of the pinion 209 is translated by the pin 208 into reciprocatory movement of the connecting rod 206. In turn this movement of the connecting rod 206 causes the arm 200 to oscillate and the hammer 199 to strike the bell 60. The parts are so proportioned that when the hammer 199 strikes the bell 60, it is moving freely, i. e., the arm 200 is out of engagement with the shoulder 205.

The connecting rod 206 is guided in its reciprocatory movement by a lug 210 which projects into a slot 211 in the base plate 68.

In order to provide for moving the connecting rod 206 to the inoperative position, as shown in Figures 17, 18, 19 and 20, it is provided with a forwardly turned shoulder 212 with which a nose 213 of an alarm release lever 214 is arranged to engage, as shown in these figures. The alarm release lever 214 is rockably mounted by a screw 215 on the base plate 68 and has a nose portion 216 which is arranged to be engaged by the outer circular edge 217 of the stop plate 167. The edge 217 is recessed as indicated at 218 to permit the nose 216 to move therein and thereby permit the alarm release lever 214 to rock in a clockwise direction to the position shown in Figure 14.

The alarm release lever 214 is biased in a

clockwise direction by a coil compression spring 222 which bears against a depending arm 223 and against one tine 224, Figure 5, of the cut-out slide 58. Another tine 225 of the cut-out slide 58 is arranged to move back of the depending arm 223 for holding the alarm release lever 214 in the position thereof, shown in Figures 17-18-19-20 of the drawings.

It will thus be seen that the position of the alarm release lever 214 may be controlled not only by the control lever 33 but also by the cut-out slide 58. Thus, if it is desired that the alarm not be sounded at the time that the switch mechanism is operated, the cut-out slide 58 may be left in the innermost position where it locks the alarm release lever 214 in the position shown in Figure 18, for example. Thus, even though the stop plate 167 occupies the position shown in Figure 14, the nose 216 is prevented from moving into the recess 218.

In describing the operation of the clock mechanism disclosed herein attention is called to the fact that the control lever 33 may be manually set to any of the positions thereof shown in Figures 3a-3e. If it is desired that the clock mechanism be used only for the purpose of indicating time, then the control lever 33 is positioned as shown in Figure 3a and in Figure 18. Here it will be observed that the shoulder 190 is locked behind the stop 196, the switch blade 90 is in the open position with the contact buttons 92 and 93 separated and the alarm release lever 214 holds the connecting rod 206 in the inoperative position. Thus even though the cut-out slide 58 may be withdrawn to the position shown in Figure 5, the alarm mechanism is held inoperative.

But when it is desired to preset the mechanism to operate at any time in the second twelve hours, the control lever 33 is moved to compress the spring 168, as indicated in Figure 16, and the spring 168 moves the stop plate 167 until the stop 173 engages the stop pin 137, as shown in Figure 19. The corresponding position of the control lever 33 is shown in Figure 3b. Either before or after shifting the control lever 33 to the position shown in Figure 3b the control set nob 55 is turned to set the adjustable dial 27 so that the index 28 is located at the time in the second 12 hours that it is desired to have the alarm and switch mechanism functioning. It will be understood that the adjustable dial 27 may have been set previously to this desired time. In such case all that is necessary is to release the control lever 33 for movement to the position shown in Figure 3b.

When the adjustable dial 27 is moved to the preset position, the trip pin 114, Figure 7, carried thereby is set in a corresponding position to engage the radial edge 161 of the dog 156 when the time wheel 126 is rotated by the motor 75 to the corresponding position. The continued rotation of the time wheel 126 causes the actuating member 149 to rock above its pivot pin 152. As previously described the first result of this movement is to permit the spring 146 to move the pawl actuating arm 145 so as to bring the pawl 143 into engagement with the ratchet wheel 134. The dog 156 is released from the trip pin 114 at the time in the first 12 hours which is 12 hours ahead of the preset time. The actuating member 149 then moves with a snap action under the force applied by the spring 153 to impact the arm 145. This causes the ratchet wheel 134 to be rocked slightly and to carry with it the

stop pin 137 out of engagement with the stop 173. The spring 168 immediately moves the stop plate 167 in a clockwise direction and the flat edge 175 of the arcuate slot 172 directs the stop pin 137 into engagement with the stop 174, as shown in Figure 17. In this position it will be noted that the contact buttons 92 and 93 of the switch mechanism are still separated and that the alarm release lever 214 is still held in the inoperative position. It will be noted further that the control lever 33 has been moved to the position shown in Figure 3c.

The time wheel 126 continues to rotate through the next twelve hours whereupon the nose 158 of the dog 156 again engages the trip pin 114 and the stop pin 137 is again moved as previously described by movement of the ratchet wheel 134. In both instances the stop pin 137 moves away from the stop 174. The movement of the ratchet wheel 134 causes the stop pin 137 to move out of engagement with the stop 174 and thereupon the spring 168 swings the stop plate 167 to the position shown in Figure 14. Here its movement in clockwise direction is limited by the shoulder 190 engaging the extension 191. In this position the nose 193 of the cam 192 moves out of engagement with the pin 194 and the switch operating arm 102 is moved relative to the shaft 84 by the inherent resiliency of the switch blade 90 until the circuit is completed through the contact buttons 92 and 93. The circuit is then completed for energizing the device such as the electrical appliance, radio and the like.

In this position of the multiple stop plate 167 the nose 216 of the alarm release lever 214 is located in the recess 218, assuming that the cut-out slide 158 has been withdrawn, the spring 222 urging the alarm release lever 214 to this position. The connecting rod 206 then moves so that the pin 208 is engaged and the connecting rod is oscillated thereby. The hammer 199 then repeatedly strikes the bell 60 to give the alarm and notify the operator that the switch has been closed.

The alarm continues to ring until the control lever 33 either is moved to the position shown in Figure 3e and in Figure 20 where the switch remains closed while the alarm is shut off or the control lever 33 is moved to any of the positions shown in Figures 3a-3b-3c where both the switch and the alarm are cut off.

When the control lever 33 is moved to the position shown in Figure 3b, it will be understood that the numerals 24 on the indicator plate 33 will appear in the aperture 64. Thus by inspecting the indicator plate 63 it is possible to quickly determine the operative condition of the clock. After the stop pin 137 has been moved away from the stop 173, either by actuation of the ratchet wheel 134 or by manual operation as a result of movement of the pin release arm 179, the stop plate 167 is moved by the spring 168 until the stop pin 137 engages the stop 174. In this position the numerals 12 on the indicator plate 63 are visible in the aperture 64, as shown in Figure 3. If desired, suitable indicia may be provided on the indicator plate 63 which will be visible for the positions of the control lever 33 as indicated in Figures 3a-3d-3e.

If it is desired that the alarm and/or switch be operated at any time during the next twelve hours, the control lever 33 is initially set to the position shown in Figures 3c-17. The dog 56 in its first engagement thereafter with the trip pin 114 will effect movement of the stop plate 167

to the position shown in Figure 14 where, if the cut-out slide 58 is withdrawn, both the alarm and the switch will be operated. The control lever 33, as before, may then be moved to the position shown in Figures 3e-20 where the alarm will be cut out while the switch will remain closed.

It will now be apparent that the present invention provides for operating an alarm signal and a switch at any time in either a first or second 12 hour period. The alarm indicates that the switch has been actuated. On the further movement of the control lever 33 the alarm may be cut out while the switch remains closed. Alternatively the alarm cut-out slide 58 may be moved inwardly so as to prevent operation of the alarm until the same is withdrawn.

Ordinarily after the electrical apparatus has been operated for the desired period of time, it may be de-energized by moving the control lever 33 to any of the positions shown in Figures 3a—3b—3c. If the control lever 33 is moved back to the position shown in Figure 3a then, of course, no operation can take place. However, if the control lever 33 is reset to the position shown in Figure 3b, the alarm will be operated, assuming that the cut-out slide 58 is withdrawn, and the switch will be closed at the preset time during the second succeeding twelve hours. For example, it may be desired to have a radio set turned on at seven o'clock each evening. The index 28 is adjusted by the control set nob 55' to a position opposite the numeral 7 on the dial 22. The control lever 33 is moved to the position shown in Figure 3b and the cut-out slide 58 is withdrawn. After the alarm has been operated and the switch closed and the radio set has been energized for the desired interval, the control lever 33 can be reset to the position shown in Figure 3b. Thereupon the cycle of operations previously described will be repeated.

Since certain further changes can be made in the foregoing construction and different embodiments of the invention can be made without departing from the spirit and scope thereof, it is intended that all matter shown on the accompanying drawings and described hereinbefore shall be interpreted as illustrative and not in a limiting sense.

What is claimed as new is:

1. A timing mechanism comprising, in combination, a time wheel arranged to be rotated once every twelve hours, tripping means thereon, mechanism to be operated at a predetermined time more than twelve hours after a given time, means arranged to be operated by said tripping means from a first position to a second position during one revolution of said time wheel without operating said mechanism and from said second position to a third position during the next revolution of said time wheel to effect operation of said mechanism, a member for operating said tripping means, and means for manually presetting said member.

2. A timing mechanism comprising, in combination, a time wheel arranged to be rotated once every twelve hours, tripping means thereon, mechanism to be operated at a predetermined time more than twelve hours after a given time, means arranged to be operated by said tripping means from a first position to a second position during one revolution of said time wheel without operating said mechanism and from said second position to a third position during the next revolution of said time wheel to effect operation of

said mechanism, manually operable means for presetting said means in said first position, a member for operating said tripping means, and means for manually presetting said member.

3. A timing mechanism comprising, in combination, a time wheel arranged to be rotated once every twelve hours, tripping means thereon, an alarm mechanism and a switch mechanism to be operated at a predetermined time more than twelve hours after a given time, means arranged to be operated by said tripping means from a first position to a second position during one revolution of said time wheel without operating either of said mechanisms and from said second position to a third position during the next revolution thereof to effect operation of both of said mechanisms, manually operable means for moving said means to a fourth position to restore said alarm mechanism to the inoperative condition while leaving said switch mechanism in the operated condition, a member for operating said tripping means, and means for manually presetting said member.

4. A timing mechanism comprising, in combination, a time wheel arranged to be rotated once every twelve hours, tripping means thereon, an alarm mechanism and a switch mechanism to be operated at a predetermined time more than twelve hours after a given time, means arranged to be operated by said tripping means from a first position to a second position during one revolution of said time wheel without operating either of said mechanisms and from said second position to a third position during the next revolution thereof to effect operation of both of said mechanisms, manually operable means for presetting said means in said first position and moving said means to a fourth position to restore said alarm mechanism to the inoperative condition while leaving said switch mechanism in the operated condition, a member for operating said tripping means, and means for manually presetting said member.

5. A timing mechanism comprising, in combination, a time wheel arranged to be rotated once every twelve hours, tripping means thereon, and alarm mechanism to be operated at a predetermined time more than twelve hours after a given time, means arranged to be operated by said tripping means from a first position to a second position during one revolution of said time wheel without operating said alarm mechanism and from said second position to a third position during the next revolution thereof to effect operation of said alarm mechanism, manually operable means for moving said means to a fourth position to restore said alarm mechanism to the inoperative condition, a member for operating said tripping means, and means for manually presetting said member.

6. A timing mechanism comprising, in combination, a time wheel arranged to be rotated once every twelve hours, tripping means thereon, a switch mechanism to be operated at a predetermined time more than twelve hours after a given time, means arranged to be operated by said tripping means from a first position to a second position during one revolution of said time wheel without operating said alarm mechanism and from said second position to a third position during the next revolution thereof to effect operation of said switch mechanism, manually operable means for moving said means to a fourth position to restore said alarm mechanism to the inoperative condition while leaving said switch

mechanism in the operated condition, a member for operating said tripping means, and means for manually presetting said member.

7. A timing mechanism comprising, in combination, a timing motor, a switch, a multiple stop lever for operating said switch, said lever being arranged to be located in at least four different positions, spring means for moving said lever from a first position to the other positions, locking means for holding said lever in its first position, manual means for releasing said locking means to permit said lever to move to its second position, cyclically operable means driven by said motor, and trip means operated by said cyclically operable means during one cycle of its operation for releasing said lever to move to its third position and during the next cycle for releasing said lever to move to its fourth position whereupon said switch is operated from one position to another.

8. A timing mechanism comprising, in combination, a timing motor, a switch, an alarm signal, a multiple stop lever for operating said switch and signal, said lever being arranged to be located in five different positions, spring means for moving said lever from a first position to the other positions, locking means for holding said lever in its first position, manual means for releasing said locking means to permit said lever to move to its second position, cyclically operable means driven by said motor, manually presettable trip means operated by said cyclically operable means during one cycle of its operation for releasing said lever to move to its third position and during the next cycle for releasing said lever to move to its fourth position whereupon said switch is operated from one position to another and said alarm signal is operated, and stop means for arresting said lever in said fourth position, said manual means being operable to permit said lever to move past said stop means to its fifth position in which said alarm signal ceases to operate while said switch is unaffected.

9. A timing mechanism comprising, in combination, a timing motor, an alarm signal, a multiple stop lever for operating said signal, said lever being arranged to be located in five different positions, spring means for moving said lever from a first position to the other positions, locking means for holding said lever in its first position, manual means for releasing said locking means to permit said lever to move to its second position, cyclically operable means driven by said motor, manually presettable trip means operated by said cyclically operable means during one cycle of its operation for releasing said lever to move to its third position and during the next cycle for releasing said lever to move to its fourth position whereupon said alarm signal is operated, and stop means for arresting said lever in said fourth position, said manual means being operable to permit said lever to move past said stop means to its fifth position in which said alarm signal ceases to operate.

10. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel, a spring for biasing said actuating member to im-

pact said actuating arm and holding the same against the biasing force of its spring, a dog pivoted on said actuating member and having limited movement relative thereto, and a spring biasing said dog outwardly with respect to said actuating member; a ratchet wheel coaxially mounted with said time wheel and rockable independently thereof and arranged to be engaged by said pawl when said actuating arm is disengaged by said actuating member and the former is free to be moved by its spring, a stop pin extending from said ratchet wheel through an aperture in said base plate, a stop finger in said aperture integral with said base plate, a spring interconnecting said stop pin and said base plate for biasing the former against said stop finger, a dial rotatable coaxially with and independently of said time wheel, manual means for rotating said dial to any desired position, a trip pin carried by said dial and disposed on rotation thereof in one direction to pass by said dog without moving said actuating member and on relative rotation in the opposite direction with respect to said time wheel to rock said actuating member and tension its spring and then release the same to strike said actuating arm whereupon said ratchet wheel is rocked by said pawl to move said stop pin away from said stop finger, a shaft rockably mounted normal to said base plate, a multiple stop lever carried by said shaft, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the movement of said stop pin on disengaging one step in response to actuation of said ratchet wheel into engagement with the next step, a manually operable control lever rockably mounted on said shaft and having limited movement relative to said multiple stop lever for moving the same to its various operative positions, an arm rockably mounted on said multiple stop lever and operable by said control lever during said limited movement thereof for moving said stop pin off of said steps to permit said multiple stop lever to be moved by its spring to the next position thereof, a spring for holding said arm on said stop lever in retracted position, a cam rotatable with said shaft, a switch operated by said cam to the closed position only after said stop pin has been moved out of engagement with the last of said steps and said multiple stop lever has been moved to the next position by its spring, an alarm bell hammer pivoted on said base plate for striking an alarm bell, means including a connecting rod operatively interconnecting said motor and said bell hammer for reciprocating the latter to ring the bell, an alarm release lever rockably mounted on said base plate and arranged in operative position to cooperate with said connecting rod for disestablishing said operative connection between said motor and said bell hammer, a nose portion on said alarm release lever arranged to be engaged by the outer curved surface of said multiple stop lever for holding said alarm release lever in its operative position, said outer curved surface having a re-entrant portion for receiving said nose portion only when said multiple stop lever has been moved to its said next position to permit said release lever to move to inoperative position, and manually operable means for locking said alarm release lever in operative position.

11. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel, a spring for biasing said actuating member to impact said actuating arm and holding the same against the biasing force of its spring, a dog pivoted on said actuating member and having limited movement relative thereto, and a spring biasing said dog outwardly with respect to said actuating member; a ratchet wheel coaxially mounted with said time wheel and rockable independently thereof and arranged to be engaged by said pawl when said actuating arm is disengaged by said actuating member and the former is free to be moved by its spring, a stop pin extending from said ratchet wheel through an aperture in said base plate, a stop finger in said aperture integral with said base plate, a spring interconnecting said stop pin and said base plate for biasing the former against said stop finger, a dial rotatable coaxially with and independently of said time wheel, manual means for rotating said dial to any desired position, a trip pin carried by said dial and disposed on rotation thereof in one direction to pass by said dog without moving said actuating member and on relative rotation in the opposite direction with respect to said time wheel to rock said actuating member and tension its spring and then release the same to strike said actuating arm whereupon said ratchet wheel is rocked by said pawl to move said stop pin away from said stop finger, a shaft rockably mounted normal to said base plate, a multiple stop lever carried by said shaft, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the movement of said stop pin on disengaging one step in response to actuation of said ratchet wheel into engagement with the next step, a manually operable control lever rockably mounted on said shaft and having limited movement relative to said multiple stop lever for moving the same to its various operative positions, an arm rockably mounted on said multiple stop lever and operable by said control lever during said limited movement thereof for moving said stop pin off of said steps to permit said multiple stop lever to be moved by its spring to the next position thereof, a spring for holding said arm on said stop lever in retracted position, a cam rotatable with said shaft, and a switch operated by said cam to the closed position only after said stop pin has been moved out of engagement with the last of said steps and said multiple stop lever has been moved to the next position by its spring.

12. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel, a

spring for biasing said actuating member to impact said actuating arm and holding the same against the biasing force of its spring, a dog pivoted on said actuating member and having limited movement relative thereto, and a spring biasing said dog outwardly with respect to said actuating member; a ratchet wheel coaxially mounted with said time wheel and rockable independently thereof and arranged to be engaged by said pawl when said actuating arm is disengaged by said actuating member and the former is free to be moved by its spring, a stop pin extending from said ratchet wheel through an aperture in said base plate, a stop finger in said aperture integral with said base plate, a spring interconnecting said stop pin and said base plate for biasing the former against said stop finger, a dial rotatable coaxially with and independently of said time wheel, manual means for rotating said dial to any desired position, a trip pin carried by said dial and disposed on rotation thereof in one direction to pass by said dog without moving said actuating member and on relative rotation in the opposite direction with respect to said time wheel to rock said actuating member and tension its spring and then release the same to strike said actuating arm whereupon said ratchet wheel is rocked by said pawl to move said stop pin away from said stop finger, a shaft rockably mounted normal to said base plate, a multiple stop lever carried by said shaft, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the movement of said stop pin on disengaging one step in response to actuation of said ratchet wheel into engagement with the next step, a manually operable control lever rockably mounted on said shaft and having limited movement relative to said multiple stop lever for moving the same to its various operative positions, an arm rockably mounted on said multiple stop lever and operable by said control lever during said limited movement thereof for moving said stop pin off of said steps to permit said multiple stop lever to be moved by its spring to the next position thereof, a spring for holding said arm on said stop lever in retracted position, a cam rotatable with said shaft, and a switch operated by said cam to the closed position only after said stop pin has been moved out of engagement with the last of said steps and said multiple stop lever has been moved to the next position by its spring.

13. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel and carrying an operating dog, and a spring for biasing said actuating member to impact said actuating arm and holding the same against the biasing force of its spring; a ratchet wheel coaxially mounted with said time wheel and rockable independently thereof and arranged to be engaged by said pawl when said actuating arm is disengaged by said actuating member and the

former is free to be moved by its spring, a stop pin extending from said ratchet wheel, stop means on said base plate for said stop pin, spring means biasing said stop pin against said stop means, a dial manually rotatable coaxially with and independently of said time wheel, a trip pin carried by said dial for engaging said dog to rock said actuating member and tension its spring and then release the same to strike said actuating arm whereupon said ratchet wheel is rocked by said pawl to move said stop pin away from said stop means, a multiple stop lever carried by said base plate, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the movement of said stop pin on disengaging one step in response to actuation of said ratchet wheel into engagement with the next step, a manually operable control lever disposed in cooperative relation to said multiple stop lever for moving the same to its various operative positions, a switch arranged to be operated by said multiple stop lever from one position to another only after said stop pin has been moved out of engagement with the last of said steps and said multiple stop lever has been moved to the next position by its spring, an alarm signal, and means cooperating with said multiple stop lever when the same is in the switch operating position for effecting the operation of said alarm signal, said control lever being operable to move said multiple stop lever beyond its said next position to render said alarm signal inoperative without changing the position of said switch.

14. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel and carrying an operating dog, and a spring for biasing said actuating member to impact said actuating arm and holding the same against the biasing force of its spring; a ratchet wheel coaxially mounted with said time wheel and rockable independently thereof and arranged to be engaged by said pawl when said actuating arm is disengaged by said actuating member and the former is free to be moved by its spring, a stop pin extending from said ratchet wheel, stop means on said base plate for said stop pin, spring means biasing said stop pin against said stop means, a dial manually rotatable coaxially with and independently of said time wheel, a trip pin carried by said dial for engaging said dog to rock said actuating member and tension its spring and then release the same to strike said actuating arm whereupon said ratchet wheel is rocked by said pawl to move said stop pin away from said stop means, a multiple stop lever carried by said base plate, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the

movement of said stop pin on disengaging one step in response to actuation of said ratchet wheel into engagement with the next step, a manually operable control lever disposed in cooperative relation to said multiple stop lever for moving the same to its various operative positions, and mechanism operatively connected to said multiple stop lever and arranged to be operated thereby when it occupies certain of its operative positions.

15. A timing mechanism comprising, in combination, a base plate, a synchronous motor thereon, a time wheel rotatably mounted on said base plate and driven by said motor; a tripping mechanism comprising a pawl rockably mounted on one side of said time wheel, an actuating arm connected to and movable with said pawl and disposed on the other side of said time wheel, a spring biasing said actuating arm, an actuating member pivotally mounted on said time wheel and carrying an operating dog, and a spring for biasing said actuating member to impact said actuating arm and holding the same against the biasing force of its spring; a ratchet wheel coaxially mounted with said time wheel and rockable independently thereof and arranged to be engaged by said pawl when said actuating arm is disengaged by said actuating member and the former is free to be moved by its spring, a stop pin extending from said ratchet wheel, stop means on said base plate for said stop pin, spring means biasing said stop pin against said stop means, a dial manually rotatable coaxially with and independently of said time wheel, a trip pin carried by said dial for engaging said dog to rock said actuating member and tension its spring and then release the same to strike said actuating arm whereupon said ratchet wheel is rocked by said pawl to move said stop pin away from said stop means, a multiple stop lever carried by said base plate, a spring biasing said multiple stop lever, a plurality of steps on said multiple stop lever arranged to be engaged successively by said stop pin whereby said lever is held in positions corresponding to said steps, said steps being located along the inside of an arcuate slot in said lever the outer side of which serves to direct the movement of said stop pin on disengaging one step in response to actuation of said ratchet wheel into engagement with the next step, a manually operable control lever disposed in cooperative relation to said multiple stop lever for moving the same to its various operative positions, and a switch arranged to be operated by said multiple stop lever from one position to another only after said stop pin has been moved out of engagement with the last of said steps and said multiple stop lever has been moved to the next position by its spring.
